Specification for Design.

Patented Feb. 7, 1922.

Application filed May 12, 1921. Serial No. 469,061. Term of patent 7 years.

To all whom it may concern:

Be it known that I, PHILIP H. HEATER, a citizen of the United States, resident at Bucyrus, in the county of Crawford and State of Ohio, have invented a new, original, and ornamental Design for Tires, of which the following is a specification, reference being had to the accompanying drawing, forming part thereof.

In the drawings:

Figure 1 is a plan view of a tire, showing my new design;

Figure 2 is a transverse sectional view, on line 2—2 of Figure 1; and

Figure 3 is a sectional view, on line 3—3 of Figure 1.

I claim:

The ornamental design for a tire, as shown.

PHILIP H. HEATER.
